UNITED STATES PATENT OFFICE.

MAX BINSWANGER, OF NEW YORK, N. Y., ASSIGNOR TO NEW COLUMBIA SHIRT COMPANY, OF NEW YORK, N. Y.

REVERSIBLE CUFF.

1,097,517.

Specification of Letters Patent. Patented May 19, 1914.

Application filed August 11, 1913. Serial No. 784,191.

To all whom it may concern:

Be it known that I, MAX BINSWANGER, of New York, in the county of New York, and State of New York, have invented certain new and useful Improvements in Reversible Cuffs; and I do hereby declare the following to be a full, clear, and exact description of the invention, such as will enable others skilled in the art to which it appertains to 10 make and use the same.

This invention relates to improvements in reversible cuffs and more particularly to soft cuffs which are made integral parts of the sleeves of the shirt,—the object of 15 the invention being to minimize the number of button holes and to so locate the button holes that when the cuff is in use, only one button hole at each end of the cuff will be visible.

With this object in view, the invention 20 consists in certain novel features of construction as hereinafter set forth and pointed out in the claim.

In the accompanying drawings, Figures 1 25 and 2 are face views illustrating my improvements, and Figs. 3 and 4 are sectional views of the structures shown in Figs. 1 and 2.

1 represents a shirt sleeve and 2 the wrist 30 band thereof,—with which latter a reversible cuff 3 is made integral or securely attached centrally between the side edges of said cuff. The wearing portions of the reversible cuff are indicated at 4 and 5, the attachment of the wrist band of the sleeve being approximately at the juncture of said 35 wearing portions. Near the respective ends of the cuff portion 4 button holes 6—6 are located and these button holes are in close proximity to the juncture of the sleeve or 40 wrist band with the cuff. Near the respective ends of the sleeve or wrist band, button holes 7—7 are located in close proximity to

the juncture of the wrist band and cuff. The button holes 6—6 in the portion 4 of the cuff 45 will align with the button holes 7—7 in the wrist band for the reception of a cuff-button when the portion 5 of the cuff is exposed for use. When the cuff is reversed so as to expose the portion 4 for use, the button holes 7—7 in the wrist band will be located behind the portion 5 of the cuff and will be out of sight,—the button holes 6—6 alone serving to receive the cuff-button.

From the construction and arrangement 55 of parts above described, it will be observed that a single pair of holes in the cuff proper serve to receive the button in the two positions of the cuff.

In the drawing I have shown the various 60 button holes disposed horizontally but it is evident that said button holes may be vertically or diagonally disposed, if desired.

Having fully described my invention what I claim as new and desire to secure by 65 Letters-Patent is:

The combination of a shirt sleeve and a reversible cuff permanently attached thereto, said cuff having a single button hole near each end and adjacent to the juncture 70 of the cuff with the sleeve, and said sleeve having a button hole near each edge of its wrist portion and in proximity to its juncture of said wrist portion with the cuff so that when the cuff is in one position, the button holes therein will be just outside of the end of the sleeve, and when in its other position the button holes in the cuff will register with the button holes in the sleeve.

In testimony whereof, I have signed this 80 specification in the presence of two subscribing witnesses.

MAX BINSWANGER.
